ALONZO E. RHOADES, OF HOPE DALE, MASSACHUSETTS, ASSIGNOR TO DRAPER CORPORATION, OF HOPE DALE, MASSACHUSETTS, A CORPORATION OF MAINE.

FEELER MECHANISM FOR LOOMS.

1,416,510.

Specification of Letters Patent. Patented May 16, 1922.

Application filed June 11, 1919. Serial No. 303,360.

To all whom it may concern:

Be it known that I, ALONZO E. RHOADES, a citizen of the United States, residing at Hopedale, in the county of Worcester and 5 State of Massachusetts, have invented an Improvement in Feeler Mechanism for Looms, of which the following description, in connection with the accompanying drawings, is a specification, like characters on the 10 drawings representing like parts:

The present invention relates to that class of automatic weft replenishing looms wherein in the weft or filling, as it is sometimes called, is replenished prior to the complete 15 exhaustion of that in the shuttle, so that no blank or partial picks occur in the finished fabric. Looms of this general type are commonly known as "feeler looms," because ordinarily they are equipped with a 20 device which feels into the shuttle to detect the condition of the filling on detecting beats, and when the filling has reached substantial exhaustion; but prior to complete exhaustion, the feeler device sets in operation 25 the train of mechanism to effect replenishment of filling.

In the practical use of such feeler mechanisms there are numerous variable factors requiring consideration, and various attempts have heretofore been made to provide 30 a feeler mechanism which will be effective to perform its desired function regardless of the variable factors involved. Some of these feelers have consisted of a finger or 35 feeler member which would feel into the shuttle on a detecting beat and detect the amount of filling in the shuttle by measuring the amount between the surface of the filling carrier and the surface of the filling 40 engaged by the feeler. This difference is often very small and may only amount to one or two thicknesses of the filling itself.

One of the objects of the present invention is to provide a feeler mechanism for 45 looms which, measures or calipers the diameter of the filling carrier and filling thereon as the latter approaches but prior to complete exhaustion thereof, thereby eliminating many of the variable factors which 50 objectionably react upon the feeler mechanism and occasionally cause premature or too late operation thereof. In carrying the invention into practical effect, the feeler member is provided with a yoke-like end

formed by fingers or projections separated 55 in the direction of the diameter of the filling carrier in the shuttle, and it is supported in position independently of the lay to cause the end of the feeler member to enter the side of the shuttle and detect the condition 60 of the filling on each detecting beat. When a working supply of filling is present in the shuttle, the ends of the yoke or projections from the feeler member engage the filling mass, one at each side of the longitudinal 65 axis of the filling carrier, and as the lay moves on its detecting beat, it forces the feeler member forwardly or in the direction of lay movement, but when the filling has become substantially exhausted, the filling 70 carrier and filling enter between the members of the yoke or the projections, and the latter measure or caliper the diameter of the filling carrier and filling thereon, and through a train of mechanism effect replenishment of filling.

In the drawings:

Figure 1 is a perspective view of a loom at the feeler side, showing the present invention associated therewith;

Fig. 2 is a longitudinal sectional elevation of the feeler mechanism, showing the action of the feeler and its associated parts when a working supply of filling is present in the shuttle; and

Fig. 3 is a view similar to that of Fig. 2, showing the action of the feeler and its associated parts when the filling is substantially exhausted.

The loom frame 1 has connected thereto 90 suitable brackets 2 for supporting the transverse or change shaft 3 from which rises the arm 4 having pivoted thereto at 5 the latch 6. The latch has an end portion which, as will later appear, is adapted to be struck 95 by the weft hammer or cam follower 7 when replenishment of filling is called. Pivotedly mounted at 8 on suitable supports carried by the loom frame is the transmitter 9 having an end portion 10 underlying the latch 6 100 (Fig. 1), the other end of the transmitter being provided with an adjustable bracket 11 having a slotted portion with an inclined wall 12 over which is adapted to move at times the controller 13. The controller 13 is 105 pivotally mounted at 14 and is normally held in its rearward or inoperative position by means of a spring or other yielding

means 15, which in the present instance is indicated as a coil spring placed about the pivot support 14.

Adjustably mounted on the loom frame or 5 a suitable bracket connected thereto is a feeler stand 16 adjustable by the bolt and slot connection 17 to properly associate the feeler mechanism and relate it to the movement of the lay. The feeler stand 16 has 10 a guide arm or guard 18 extending longitudinally thereof, below which extends the end of the controller 13. Mounted for movement towards and from the front of the loom is a feeler support, which, in the present instance of the invention, comprises a 15 slide 19 having a portion 20 within the feeler stand 16. A spring 21 interposed between the portion 20 of the feeler slide and a part of the feeler stand, serves to normally maintain the feeler slide or support in its rearward or feeling position.

Pivotaly mounted on the feeler support or slide 19 at 22 is the actuator 23, the end 24 of which is normally held raised by a 25 spring actuated pin 25. Adjustably connected to the actuator 23 is the bunter 26, which, in the present instance of the invention, passes through a lug 27 connected to the actuator, and is held in adjusted position 30 by a lock nut 28, the construction being such that the bunter 26 is, under conditions to be hereinafter more fully explained, adapted to be struck by a part carried by the lay such as the shuttle wall, for instance, when 35 the filling has reached substantial exhaustion and the feeler member enters further into the shuttle. The construction thus far described may be the same as that of the well known Draper feeler mechanism, shown 40 for instance in the patent to Wood & Norrthrup No. 789,471, May 9, 1905.

Mounted on the feeler support or slide 19 is the feeler member 29 having the yoke-like end portion which may be appropriately formed by the projections or fingers 30 and 31 separated in the direction of the diameter of the filling carrier with which they coact.

The lay 32 and shuttle box 33 may be of 50 usual construction as found in filling replenishing looms, with the exception that the front wall 34 of the shuttle box is provided with an opening 35 adapted to register with an opening 36 in the side wall of the shuttle 55 when the latter is in the box at the feeler side of the loom substantially as indicated in Fig. 1.

It has heretofore been proposed to employ 60 a caliper feeler to feel for the filling in the shuttle on a detecting beat and measure the diameter of the filling carrier and filling, but in such cases the caliper feeler has usually been caused to feel into the shuttle through the top thereof. This has 65 been due to the fact that the diameter of

the filling carrier or bobbin and filling thereon at the critical moment or substantial exhaustion of filling was so great that to cause the feeling action of such caliper feeler through the side of the shuttle, would necessitate cutting the side of the shuttle through the top downward toward the base of the shuttle to an extent such as to weaken the structure and cause its rapid destruction in the operation of the loom. The present invention, therefore, has special adaptation in connection with feeler looms using cops in the shuttle, which being of less and more uniform diameter than the usual wooden bobbins, permit the use of the caliper feeler as hereinbefore described, entering the side of the shuttle through a slot such as 36, which does not materially weaken the shuttle body. In Figs. 2 and 3 the cop spindle 37 is shown with the cop or 75 paper tube 38 thereon and the filling 39 supported by the tube and spindle. The shuttle 40 may be of the usual type having the usual holding jaws, and the cop spindle 37 may be provided with a head 41 having 80 the jaw engaging rings thereon to permit the depleted carrier to be ejected and a full carrier substituted by the replenishing mechanism as well understood by those skilled in the art. 95

From the construction described it will be seen that when a working supply of filling is present in the shuttle, the filling 39 (Fig. 2) will engage the ends of the yoke or fingers 31 and, as the lay moves forward in completing its beat-up, the feeler member and its support will be moved frontwardly, such frontward movement being initiated prior to the engagement of the bunter 26 with the wall of the shuttle. 100 When, however, the filling has become substantially exhausted as indicated in Fig. 3, and the filling carrier and filling enter the yoke or between the fingers 30 and 31 of the feeler member, the latter are moved further into the shuttle before it will partake of the frontward movement of the lay, and the bunter 26 will engage the wall of the shuttle or some other portion carried by the lay and cause the actuator to be 115 turned upon its pivotal support 22 into position, such, that its front end 24 will engage the controller 13 and move it frontwardly as indicated in Fig. 3 as the lay completes its frontward beat. Movement of 120 the feeler frontwardly is preferably effected when the filling enters between the fingers 30, 31 by pressure of the filling against the abutments 30^a, 31^a, formed by the curved inner surface extending from one finger to 125 the other. By thus caliper or measuring the diameter of the filling carrier and filling at the critical time, or when a change of filling is desired, the projections or fingers 30 or 31 will embrace between them 130

thicknesses of filling at opposite sides of the axis of the filling carrier, thus more accurately measuring the amount of filling on the carrier.

5 What is claimed is:—

1. A feeler mechanism for filling replenishing looms, comprising, in combination, a feeler mounted upon a fixed portion of the loom to enter the shuttle on a detecting beat through an opening in the side of the shuttle and provided with an integrally formed yoke-like rear end adapted to pass into the shuttle through said opening and having the legs of the yoke relatively unyielding to caliper 15 per the diameter of the filling in the shuttle by entrance of the filling carrier between the spaced legs of the yoke-like end of the feeler when the filling is substantially exhausted, a feeler slide for supporting the feeler for 20 movement towards and from the front of the loom, a spring acting to normally maintain the yoke-like end of the feeler in its rearward feeling position, an actuator pivotally mounted upon the slide, a bunter carried by 25 the actuator to engage the side wall of the shuttle when the filling carrier passes into the yoke-like end of the feeler on a detecting beat, a controller adapted to be engaged by the actuator when the actuator is moved 30 by the bunter, and means positioned by the controller to effect replenishment of filling.
2. A feeler mechanism for filling replenishing looms, comprising, in combination, a feeler mounted upon a fixed portion 35 of the loom and having an integrally formed yokelike rear end adapted to enter the shuttle on a detecting beat through an opening in the side of the shuttle, the two legs of the yoke being relatively unyielding to caliper 40 the diameter of the filling in the shuttle by entrance of the filling carrier into the yoke-like end of the feeler when the filling is substantially exhausted on a detecting beat, a feeler slide supporting the feeler and mounted 45 for movement towards and from the front of the loom, a spring normally acting to

maintain the yoke-like end of the feeler in rearward position to enter the side of the shuttle as the lay beats up on a detecting beat, an actuator movably mounted upon the 50 slide and adapted to be moved to operative position upon the filling carrier passing into the yoke-like end of the feeler, a controller adapted to be engaged and positioned by the actuator when the latter is moved to its 55 operative position, said yoke-like rear end having abutments adapted to be engaged by the filling and moved forwardly upon the filling carrier passing into the yoke-like rear end, and means positioned by the controller 60 to effect replenishment of filling.

3. In a filling replenishing loom provided with a cop supporting shuttle having a feeler receiving opening in a side of the shuttle, in combination, a feeler mounted upon a fixed 65 portion of the loom and having an integrally formed yoke-like rear end, the two legs of the yoke being relatively unyielding to caliper the diameter of the filing in the shuttle by the entrance of the cop into the yoke-like 70 end of the feeler when the filling is substantially exhausted on a detecting beat, a feeler slide carrying the feeler and mounted for movement towards and from the front of the loom, a spring normally acting to 75 maintain the yoke-like end of the feeler in rearward position to enter the side of the shuttle as the lay beats up on a detecting beat, an actuator pivotally mounted on the 80 slide, a bunter carried by the actuator to engage the side wall of the shuttle when the filling carrying cop passes into the yoke-like end of the feeler on a detecting beat, a controller adapted to be engaged by the actuator when the actuator is moved by the bunter, a 85 transmitter operated by the controller, and means positioned by the transmitter to effect replenishment of filling.

In testimony whereof, I have signed my name to this specification.

ALONZO E. RHOADES.
